UNITED STATES PATENT OFFICE

HENRY E. BARROLL, OF CHICAGO, ILLINOIS, ASSIGNOR TO HENRY BARROLL & CO. INC.,
OF CHICAGO, ILLINOIS, A CORPORATION OF NEW YORK

POURING NOZZLE

Application filed January 21, 1929. Serial No. 334,066.

My invention relates to dispensing containers and pouring spouts for containers, and seals for such containers and spouts. One object of my invention is the provision of a container, for example a bottle, which shall have a pouring lip having a minimum tendency to become obstructed, and having a maximum efficiency in pouring. Another object is the combination with such a lip of a seal for the nozzle which is effective even after the pouring lip has been employed. Other objects will appear from time to time in the course of the specification and claims.

I illustrate my invention more or less diagrammatically in the accompanying drawings, wherein—

Figure 1 is a side elevation of one form of my invention;

Figure 2 is a plan view with the cap removed;

Figure 3 is a vertical axial section;

Figure 4 is a side elevation with the cap removed;

Figure 5 is a front elevation of the pouring nozzle;

Figure 6 is a plan view of a variant form of nozzle; with the cap partly broken away;

Figure 7 is a side elevation of the device of Figure 6, with the cap in section;

Figure 8 is a plan view of a further variation of my device, with the cap removed;

Figure 9 is a front elevation of the nozzle shown in Figure 8, with the cap in position;

Figure 10 is a side elevation with the cap in position; and

Figure 11 is a plan view of the cap.

Like parts are indicated by like symbols throughout the specification and drawings.

Referring first to the form of Figures 1 to 5, A generally indicates any suitable bottle or container being herein illustrated as a bottle having the neck A¹ the handle A² and the head generally indicated as A³, at the top of the neck. The head portion A³ is provided with a lower circumferential flange A⁴ and a thread or wedging member A⁵.

Formed in the upper surface of the head A is the sealing member generally indicated as B, such sealing member surrounding the pouring aperture B¹. Its upper edge lies

generally in a single plane, as indicated at B² for example in Figure 5. It is expanded laterally at one point, as at B³, to form a pouring lip, the head being cut away or recessed thereabout and therebeneath, as at B⁴. Note 55 that the extreme tip B⁵ of the lip B³ is shown in Figure 2 as terminating within the periphery of the head, whereby it will not normally engage the flange C¹ of the cap C, when such cap is in position.

In the employment of the cap the sealing member C² engages the sealing surface B, or the upper plane B² thereof. The screw threads or wedge portions C³ on the cap engage the interrupted thread A⁵ and in response to rotation of the cap and seal C² is firmly seated against the sealing member B of the nozzle or head. It will be realized that owing to the fact that the lip does not engage the flange C¹ of the cap, that it cannot 60 become sealed thereagainst by any liquid which has passed over the lip. There may be some tendency to bind against the seal C², but experience indicates that even when a container of this type is employed to dispense 65 glue or similar adhesive substances, when the cap is unscrewed the shearing action is sufficient to free the seal C² from the portion B.

In order to make this shearing action easier, 70 or to make the rotation of the cap easier I may provide laterally expanded portions C⁵ to be engaged by the handle finger.

Referring to the form of Figures 6 and 7 I may employ, in the place of the screw cap 75 above described any suitable friction cap. Therefore I employ a head D with the sealing surface or member D¹ of the pouring lip D² substantially identical with those shown in the earlier figures the head being recessed 80 or cut away as at D³ about and beneath the lip. A cap D⁴, with its seal D⁵, is held in position upon the head, as by the clamping circumferential flange D⁶. It will be realized that since the cap does not have to be rotated, 85 the cap need not be circular. In practice such caps are made circular, but an oval or other non-circular form of cap and flange may be employed.

Referring to the form of Figure 8 and 100

- following I illustrate a head E having opposed parallel sides E¹ channeled or indented as at E² to receive the inwardly extending ridges E³ of the cap generally indicated as 5 E⁴. The seal of such cap E⁵, engages the opposed sealing member E⁶ of the head. It will be understood that the pouring lip and adjacent parts are substantially as shown in the earlier forms.
- 10 It will be realized that whereas I have described and shown a practical device, nevertheless many changes might be made in size, shape, number and disposition of parts without departing from the spirit of my invention. 15 I therefore wish my description and drawings to be as in a broad sense illustrative and diagrammatic rather than as limiting me to my specific showing.
- The use and operation of my invention 20 as are follows:
- In all the forms of container or spout herein shown, I obtain the advantage of a pouring nozzle having a pouring lip which lies in the plane of and is part of a sealing 25 surface, such as B, which is engaged by a seal, such as C. This sealing surface, and the pouring lip, all lie within the normal area of the surrounding cap, whether the cap be screwed on or pressed on or slid on. In all 30 forms herein shown the pouring lip, although enclosed within or beneath the seal, is an effective pouring lip, the head being recessed or cut away beneath it, to form a drip edge. The result is a pouring container which 35 pours efficiently and which may be sealed after use, and which is sealed by the very act of restoring the cover to the pouring nozzle.
- It will be understood, that in claiming in 40 the claims wedging locking means, I wish to include not only screw threads in the sense in which the term is generally used, but any cam or wedging engagement whereby rotation of the cap draws down its seal against 45 the sealing surface on the head.
- I claim:
1. In a pouring container, a neck, a head 50 on said neck, said head including a sealing surface lying in a single plane, a pouring lip formed in said sealing surface, the head being recessed beneath said pouring lip and a cap adapted to engage said head in locking engagement, and to engage said sealing surface in sealing contact, said sealing surface 55 and pouring lip lying within the periphery of said cap.
2. In a pouring container, a neck, a generally circular head on said neck, said head 60 including a non-circular, unbroken, continuous sealing surface lying in a single plane, such sealing surface being laterally deformed to form a pouring lip, the head being recessed beneath said pouring lip, and a generally 65 circular cap adapted to engage said head in locking engagement, and to engage said sealing surface in sealing contact.
3. In a pouring container, a neck, a generally circular head on said neck, said head including a non-circular, unbroken, continuous sealing surface lying in a single plane, such sealing surface being laterally deformed to form a pouring lip, the head being recessed beneath said pouring lip, and a generally 70 circular cap adapted to engage said head in locking engagement, and to engage said sealing surface in sealing contact, the head being provided with circumferential wedging locking means, such means being interrupted adjacent the pouring lip, the cap being flanged to engage said locking wedging means.
4. In a pouring container, a neck, a head at the upper end of said neck, an interrupted wedging locking member formed in said 75 head, and a pouring lip, in line with an interruption in such locking member.
5. In a pouring container, a neck, a generally circular head on said neck, and a sealing surface lying in a single plane on the upper 80 face of said head, the plane of said sealing surface being generally perpendicular to the axis of the neck, the periphery of said head being generally circular but eccentric in relation to the axis of the neck, the sealing surface being laterally deformed to form a pouring lip, the head being recessed beneath said pouring lip, and a generally circular cap 85 adapted to engage said head in locking engagement and to engage said sealing surface in sealing contact.
6. In a pouring container, a neck, a generally circular head on said neck, and a sealing surface lying in a single plane on the upper 90 face of said head, the plane of said sealing surface being generally perpendicular to the axis of the neck, the periphery of said head being generally circular but eccentric in relation to the axis of the neck, the sealing surface being laterally deformed to 95 form a pouring lip, the head being recessed beneath said pouring lip, and a generally circular cap adapted to engage said head in locking engagement and to engage said sealing surface in sealing contact.
7. In a pouring container, a neck, a generally circular head on said neck, and a sealing surface lying in a single plane on the upper 100 face of said head, the plane of said sealing surface being generally perpendicular to the axis of the neck, the periphery of said head being generally circular but eccentric in relation to the axis of the neck, the sealing surface being laterally deformed to form a pouring lip, the head being recessed beneath said pouring lip, and a generally circular cap 105 adapted to engage said head in locking engagement and to engage said sealing surface in sealing contact.
8. In a pouring container, a neck, a generally circular head on said neck, and a sealing surface lying in a single plane on the upper 110 face of said head, the plane of said sealing surface being generally perpendicular to the axis of the neck, the periphery of said head being generally circular but eccentric in relation to the axis of the neck, the sealing surface being laterally deformed to form a pouring lip, the head being recessed beneath said pouring lip, and a generally circular cap 115 adapted to engage said head in locking engagement and to engage said sealing surface in sealing contact.

Signed at Chicago, county of Cook, and State of Illinois, this 12th day of January, 1929.

HENRY E. BARROLL.
